UNITED STATES PATENT OFFICE.

OLIVER F. TRAMPE, OF ST. LOUIS, MISSOURI.

SPARK PLUG.

Application filed March 15, 1920. Serial No. 365,777.

To all whom it may concern:

Be it known that I, OLIVER F. TRAMPE, a citizen of the United States, and a resident of the city of St. Louis and State of Missouri, have invented a new and useful Improvement in Spark Plugs, of which the following is a specification.

This invention relates to spark plugs suitable for use in connection with the igniting systems of internal combustion engines by means of which a spark is produced for igniting the combustible charge within the working cylinders of the engine.

One of the principal objects of the present invention is to simplify the construction of the spark plug and to reduce the cost of manufacturing the same. Another object is to render the production of the spark more certain. The invention consists principally in a spark plug having a stationary central electrode and a series of stationary outer electrodes, the center electrode having a plate attached thereto provided with a series of notches for cooperation with the outer electrodes. The invention further consists in the construction and combination of parts hereinafter described and claimed.

In the accompanying drawing wherein like symbols refer to like parts wherever they occur,

Fig. 1 is a central vertical section through the spark plug embodying my invention; and

Fig. 2 is an enlarged horizontal cross section on the line 2—2 in Fig. 1.

The present spark plug comprises an outer casing or shell 1 having a reduced lower shank portion 2 which is threaded to enable the spark plug to be screwed into the cylinder of an engine. A central electrode, which is in the form of a tapered metallic rod 3, is positioned within a tapered bore of a cylindrical insulating plug 4 of porcelain or other suitable material. The insulating core 45 is provided with an annular flange 5 which is seated on an annular shoulder 6 formed in the inner wall of the shell 1. The annular flange 5 of the insulating core is clamped rigidly in position within the shell 50 1 by means of a threaded bushing or sleeve 7 that is threaded into the upper end of the casing 1 and whose beveled lower end bears against the corresponding beveled upper surface of a metal washer 8. An asbestos washer 9 is arranged between the under side

of the annular flange 5 of the insulating core and the upper surface of the supporting shoulder 6 of the casing to prevent breaking of the porcelain core when the same is engaged by the bushing 7.

The central bore of the insulating core is provided with a lining of mica or other suitable material 10. The central electrode 3 projects upwardly beyond the upper end of the insulating core and is provided with a jam nut 11, the tightening of which draws the tapered electrode tightly into the tapered bore and thus prevents the escape of gas.

The upper end of the spark plug is provided with a cap 12 of porcelain or other suitable material which is sleeved on the upper end of the insulating core. The upper end of the central electrode 3 projects through the cap 12 and has a terminal or binding screw 13 threaded thereon for connecting the usual wire of the igniting system to the central electrode. The wire is clamped between the under surfaces of the nut 13 and the upper surface of a metal washer 14. This washer is sleeved on the upper end of the central electrode and is supported on the upper surface of the porcelain cap 12. The cap 12 surrounds the upper end of the central electrode and is held in position by the binding nut 13. An asbestos washer or gasket 15 is arranged between the lower end of the cap 12 and the upper surface of the tubular nut 7 to cushion the upper end of the cap and to seal the joint.

The lower end portion of the central electrode projects below the lower end of the insulating core and has a reduced threaded portion 16 on which is sleeved a circular metal plate 17. A nut 18 is threaded on the reduced end portion 16 of the central electrode and bears against the plate 17, thus firmly clamping said plate against the shoulder formed by the reduced end portion of the central electrode. The peripheral edge of the circular plate 17 is provided with a series of equally spaced semicircular notches 19. The lower end of the casing 1 is provided with a circular series of electrode pins 20 which are pressed into the casing and extend downwardly therefrom. The pins extend into the notches 19 and are arranged concentric therewith. This arrangement forms a semicircular spark gap between the electrode pin 20 and the edge of the semicircular

notch 19 in the plate 20. The plate 20 is prevented from rotating on the reduced portion of the central electrode, thereby maintaining a uniform width of spark gap between the edge of the notches 19 and the outer surface of the electrode pins 20, by means of a web or key portion 21, which projects from one side of the reduced portion 16 of the central electrode and fits into a slot 10 formed in the plate 17. With the hereinbefore described arrangement, the upper end of the insulating plug is enclosed by the porcelain cap 12, and this cap, when broken, can be readily replaced at only slight expense; whereas with the usual type of spark plug, the projecting portion of the insulating plug is unprotected and is liable to be broken, thereby necessitating replacement of the entire insulating core. The semicircular notches 19 in the plate 17, which embrace the outer electrode pins 20 provide a greater area of exposed surface between the pins and their respective notches, thus enabling a larger and more intensified spark to be produced. The number of sparking points assures the production of a spark even though some of the electrode pins become fouled.

Obviously the hereinbefore described construction admits of considerable modification 30 without departing from the invention. Therefore, I do not wish to be limited to the

exact details of construction shown and described.

What I claim is:

1. A spark plug comprising a shell having an outer electrode projecting therefrom, an insulating core, a central electrode extending through said insulating core, and a plate secured to the lower end of said central electrode, said plate having an opening into which said outer electrode projects. 35

2. A spark plug comprising a shell having an outer electrode pin projecting from its lower edge, an insulating core, a central electrode extending through said insulating core, a plate secured to the lower end of said central electrode, means for preventing the rotation of said plate with respect to said central electrode, said plate having a notch in its edge into which said outer electrode pin projects. 45

3. A spark plug comprising a shell having a series of electrode pins extending therefrom, an insulating core within said shell, a central electrode extending through said core, a disk secured to the lower end of said central electrode, said disk having a series of notches formed in its outer end into which said electrode pins project. 55

Signed at St. Louis, Missouri, this 10th 60 day of March, 1920.

OLIVER F. TRAMPE.
